US00D778658S

(12) **United States Design Patent** (10) Patent No.: **US D778,658 S**
(45) Date of Patent: ** Feb. 14, 2017

(54) **SCULPTED CHAIR ARM SET**

(71) Applicant: **EZ AS A DRINK PRODUCTIONS, INC.**, Reno, NV (US)

(72) Inventors: **Viktor Kalvachev**, Sofia (BG); **Angel Petkov**, Sofia (BG)

(73) Assignee: **EZ AS A DRINK PRODUCTIONS, INC.**, Reno, NV (US)

(**) Term: **14 Years**

(21) Appl. No.: **29/513,417**

(22) Filed: **Dec. 30, 2014**

(51) LOC (10) Cl. **06-04**

(52) U.S. Cl.

USPC **D6/716.2**

(58) **Field of Classification Search**

USPC D6/334-36, 364-67, 374, 376, 379, 380, D6/716, 716.1-716.4; 297/411.2, 411.27, 297/411.35, 411.36, 411.37, 463.1

(57) **CLAIM**

The ornamental design for a sculpted chair arm set, as shown and described.

DESCRIPTION

FIG. 1 is a perspective view of the sculpted chair arm set; FIG. 2 is a front-side view of the sculpted chair arm set; FIG. 3 is a back-side view of the sculpted chair arm set; FIG. 4 is a left-side view of the sculpted chair arm set; FIG. 5 is a right-side view of the sculpted chair arm set; FIG. 6 is a top-side view of the sculpted chair arm set; FIG. 7 is a bottom-side view of the sculpted chair arm set; and, FIG. 8 is a perspective view on the sculpted chair arm set shown with a chair to provide context. The broken lines shown are for the purpose of illustrating environmental subject matter and form no part of the claimed design.

1 Claim, 8 Drawing Sheets
